TIME MODULATION PULSE SYSTEM

Ronald Bradley Shepherd, London, England, assignor to Standard Telephones and Cables Limited, London, England, a British company

Application August 11, 1943, Serial No. 498,205
In Great Britain September 11, 1942

16 Claims. (Cl. 179—171.5)

1

The present invention relates to electrical pulse transmission systems and is principally concerned with arrangements for obtaining time-modulated pulses.

According to the invention, there is provided an electrical pulse transmission system comprising means for supplying respectively each of two saw-tooth wave generators with synchronising alternating voltages of the same frequency but differing in phase, means for varying the phase difference in accordance with a modulating signal, and means for combining the saw-tooth waves from the two generators to produce a series of regularly repeated rectangular pulses time-modulated in accordance with the signal.

The invention may alternatively comprise a system for deriving time-modulated electrical pulses from two saw-tooth wave generators, comprising a variable phase splitter controlled by a modulating signal and adapted to transmit two separate synchronising voltages having the same frequency and a variable phase difference from a sinusoidal oscillator to the two generators respectively, and a mixing device for subtracting one saw-tooth wave from the other to produce rectangular pulses.

According to a different aspect, the invention consists in the method of time-modulating a series of regularly repeated electrical pulses which comprises synchronising two saw-tooth generators with alternating voltages having the same frequency and different phase, varying the phase difference according to a modulating signal and combining the outputs of the generators to obtain rectangular pulses.

The invention will be explained with reference to the accompanying drawings in which:

Fig. 1 shows wave-form diagrams used for explaining the invention;

Fig. 2 shows a block schematic diagram of the principle of the invention;

Figs. 3 and 4 show schematic circuit diagrams of a variable phase splitter according to the invention; and

Fig. 5 shows a schematic circuit diagram of a mixer according to the invention.

Fig. 6 shows a schematic circuit diagram of a system according to Fig. 2 in which the phase splitter shifts the phase of both component waves derived from the oscillator.

Fig. 7 shows a system with two phase splitters utilizing directly heated thermistors.

Fig. 8 shows a system operating on the principle of Fig. 4 but with two phase splitters instead of one.

2

It is well known that rectangular pulses may be obtained by combining a series of saw-tooth waves with a similar series of waves having the same amplitude and frequency, which have been inverted and displaced in phase. This is shown in Fig. 1 where the curve A represents a series of saw-tooth voltage waves having a period T and amplitude V . Curve B shows the inverted waves which have been displaced by a time t with respect to the waves A. If these two series of waves are added together in a suitable mixer the rectangular pulses C are produced, having a total height V , and period T . The positive portions have a voltage proportional to $t V/T$ and a width $T-t$, and the negative portions have a voltage proportional to $(T-t) V/T$ and a width t . By well known arrangements unidirectional pulses of either sign, having width $T-t$ or t , as desired, may be derived from the pulses C. It may be noted that the phase difference F between the waves A and B is $2\pi t/T$.

Referring to Fig. 6, the phase splitter PS has two parts PS_1 and PS_2 , each of which comprises a bridge network having two condensers and two indirectly heated thermistors. The two thermistors in PS_2 have temperature coefficients opposite to those of the two in PS_1 , those in PS_1 having a positive temperature coefficient and those in PS_2 a negative temperature coefficient, or vice versa. A sinusoidal oscillator O is connected to the input diagonal terminals of PS_1 and PS_2 in parallel, and the heating coils of PS_1 and PS_2 are supplied in parallel from a source of modulating signals M at terminals 3 and 4. The output diagonal terminals of the network PS_1 are connected, through wave filter WF-1 if desired, to terminals $a-a$, leading to the input terminals of sawtooth generator SG_1 . The output diagonal terminals of network PS_2 are connected, through wave filter WF-2 if desired, to terminals $b-b$ which in turn lead to the input of sawtooth generator SG_2 . The output terminals of sawtooth generators SG_1 and SG_2 are connected in a mixing circuit M like that shown in Fig. 5, or in an equivalent arrangement, in such a way that a difference voltage appears at terminals 5, 6 as explained in connection with Fig. 5.

In Fig. 6 each component of the wave from oscillator O is shifted in phase by substantially the same amount but in opposite directions so that the resultant pulses have leading and trailing edges shifted in opposite directions with respect to the center line of the pulse. The center

line of the pulse has a phase position or time position corresponding to the phase of the unshifted oscillations from O.

Thus, if the signal voltage increases, raising the temperature of the thermistors in PS₁ and PS₂, for example, the resistances of the thermistors in PS₁ may be assumed to increase while those in PS₂ decrease. If this change causes a phase lag in the output of PS₁, then the same change causes a phase lead in PS₂. Similarly, when the signal voltage from M decreases, the resistances in PS₁ will decrease while those in PS₂ increase, and a phase lead is produced in the output of PS₁ with a phase lag in PS₂.

Assuming that A in Fig. 1 represents the output wave from SG₁ and B the output wave from SG₂ when there are no signals from M, then A will be shifted slightly to the right for a lag in PS₁ due to signal from MS and B will be shifted slightly to the left for a lead in PS₂ due to the same signal from MS. The distance t will become smaller and the distance $(T-t)$ larger so that the (positive) pulse is widened. If the signal changes so that A is shifted to the left and B to the right, t becomes larger, $(T-t)$ becomes smaller, and the pulse is narrowed.

The width of the unmodulated pulse is dependent on the initial phase difference between the outputs of PS₁ and PS₂, that is, the phase difference when there is no input signal from M. In order that the leading and trailing edges of a pulse shall shift equal amounts, to give a symmetrical double-modulation effect, a given change in signal at M should be made to produce equal and opposite phase shifts in PS₁ and PS₂.

There are various obvious modifications of the circuit of Fig. 6, such as connecting the heating coils of the thermistors in parallel instead of in series, or adding any desired auxiliary resistances in the heating coil circuits. If the heating coils are omitted entirely, the modulating current is supplied at terminals 1-2 along with current from oscillator O; in this case the wave filters WF-1 and WF-2 are necessary to eliminate the modulating current from the output. These modifications have been described in connection with Figs. 3 and 4, and apply as well to Fig. 6.

Fig. 7 illustrates a system utilizing directly heated thermistors instead of indirectly heated thermistors. As indicated, the modulating current is supplied at terminals 1, 2 along with synchronizing current from the oscillator, and the heating coils r_1 and r_2 are lacking. In other respects the system is closely similar to that utilizing directly heated thermistors. The operation of the system is believed to be obvious.

Fig. 8 shows a two phase-splitter system each bridge circuit of which operates on the principle of the circuit shown in Fig. 4. That is, the capacity of one arm of each bridge is varied by varying that component of the capacity of the arm which is under control of the tube, VT-1 or VT-2. The modulating current, suitably rectified to provide variable bias for the grid of the tube, varies the amplification factor of the tube and so varies the effective tube capacity to unbalance the bridge. This produces phase shift in the bridge output current. By applying biases of reversed signs to VT-1 and VT-2 the phase shifts are produced in opposite directions, giving rise to the production of two sawtooth waves shifted in opposite directions. When combined in the mixer M the two sawtooth waves produce doubly modulated rectangular pulses in a man-

ner analogous to that described in connection with Fig. 6.

The pulses so obtained may be time-modulated by varying the phase difference F in accordance with a modulating signal which varies t (or $T-t$) without changing T . The manner in which this may be done is shown in Fig. 2, in which an oscillator O supplies alternating current at frequency $1/T$, and having preferably a sinusoidal form, to a variable phase splitter PS. This is arranged to supply two similar saw-tooth generators SG-1 and SG-2 with synchronising voltages of frequency $1/T$ and differing in phase by F , which is controlled by a modulating signal applied at MS. The saw-tooth generators SG-1 and SG-2 may be of any suitable type, and the outputs are connected to a mixer M where the two saw-tooth waves are combined to form the pulses. The mixer may contain the means for inverting one of the waves and for making the resulting pulses unidirectional. The output of the mixer is connected to the apparatus (not shown) in which the pulses are to be used.

The means for varying the phase difference F in the phase splitter PS is not shown in Fig. 2 and may take a number of forms two of which are shown respectively in Figs. 3 and 4. The arrangement shown in Fig. 3 takes advantage of the special properties of thermistors, which are thermally sensitive resistance elements.

Thermistors have been in use for some years and are characterised by a temperature coefficient of resistance which may be either positive or negative and which is moreover many times the corresponding coefficient for a pure metal such as copper. This property renders thermistors particularly suitable for a variety of special applications in electric circuits.

Various different materials are available for the resistance element of a thermistor, these various materials having different properties in other respects; as one example, a resistance material having a high negative temperature coefficient of resistance comprises a mixture of manganese oxide and nickel oxide, with or without the addition of certain other metallic oxides, the mixtures being suitably heat treated.

Thermistors have been employed in two different forms: (a) known as a directly heated thermistor and comprising a resistance element of the thermally sensitive resistance material provided with suitable lead-out conductors or terminals, and (b) known as an indirectly heated thermistor comprising the element (a) provided in addition with a heating coil electrically insulated from the element. A directly heated thermistor is primarily intended to be controlled by the current which flows through it and which varies the temperature and also the resistance accordingly. Such a thermistor will also be effected by the temperature of its surroundings and may therefore be used for thermostatic control and like purposes with or without direct heating by the current flowing through it. An indirectly heated thermistor is chiefly designed to be heated by a controlling current which flows through the heating coil and which will usually, but not necessarily, be different from the current which flows through the resistance element, but this type of thermistor may also be subjected to either or both of the types of control applicable to a directly heated thermistor.

More detailed information on the properties of thermistors will be found in an article by

G. L. Pearson in the Bell Laboratories' Record, Dec. 1940, page 106.

In this specification any resistances not actually referred to as thermistors are ordinary constant resistances whose values do not depend appreciably on the current flowing through them.

Referring to Fig. 3, the phase splitter PS comprises a bridge network comprising two condensers C_1 and C_2 , and the resistance elements R_1 and R_2 of two indirectly heated thermistors T_1 and T_2 , arranged in opposite arms as shown. The synchronising alternating voltage is supplied at terminals 1 and 2, and is applied through a wave filter WF-1 to the saw-tooth generator SG-1 (not shown in Fig. 3). It is also applied to one pair of diagonal terminals of the bridge network, the other pair of terminals being connected to the saw-tooth generator SG-2 (not shown), through a second wave filter WF-2.

It is well known that the phase of the synchronising voltage supplied to WF-2 will differ from that supplied to WF-1 by an amount depending on the values of the impedances in the bridge arms, and the value of the phase difference can be changed by suitably changing any or all of these impedances. In Fig. 3 the heating coils r_1 and r_2 of the thermistors are shown connected in series to a pair of input terminals 3 and 4 to which is supplied a modulating current which varies in accordance with some signal voltage. The thermistors should both have temperature coefficients of the same sign which, however, can be positive or negative as desired. As the signal voltage increases, for example, the temperature of both the thermistors will be raised and their resistance will be changed in the same direction. This will change the phase of the current supplied to the wave filter WF-2; and will in turn change the phase difference F between the two saw-tooth waves and also the width of the pulses in the manner already explained. Similarly, when the signal voltage decreases, F will be changed in the opposite direction. It will be evident that by changing the sign of the temperature coefficients of the thermistors, the changes in F will simply be reversed.

The two filters WF-1 and WF-2 should be designed to pass substantially only the synchronising frequency, in order to eliminate any extraneous frequencies which may be present and which might affect the proper synchronising of the saw-tooth waves. The filters are, however, not absolutely essential to the working of this arrangement.

It will be understood, of course, that the heating coils r_1 and r_2 could be connected in parallel instead of in series, and any other auxiliary resistances could be added in the heating coil circuit in any desired way.

By a modification of Fig. 3, the two thermistors could be of the directly heated type, in which case the heating coils r_1 and r_2 shown in Fig. 3 would not exist, and their connections would accordingly be left out. The modulating currents are in this case supplied with the synchronising currents at terminals 1 and 2 and flow with them through the bridge, variably heating the thermistors and changing their resistances. The wave filters WF-1 and WF-2 are in this case essential in order to exclude the modulating currents from the saw-tooth generators.

The arrangement shown in Fig. 3 is only suitable for relatively low frequencies on account of the time lag in the response of the thermistors. For high frequencies, the arrangement of Fig. 4

may be used, which depends for its operation on the property of thermionic valves known as the "Miller effect," which arises from the capacity between the anode and the control grid. It is well known that this capacity provides a feedback path in the valve and operates also to cause the effective capacity measured between the control grid and the cathode to be increased by an amount depending on the amplification factor of the valve and on the anode load. Information on this effect may be found on page 97 of "Modern Radio Communication," vol. II, by J. H. Reynier, published by Pitman (1940).

In Fig. 4 the bridge network consists of two resistances R_3 and R_4 and two condensers C_3 and C_4 . The condenser C_3 is shunted by the control grid-cathode circuit of a thermionic valve V of the variable amplification type, which is caused to vary the total effective capacity in the C_3 arm of the bridge in a manner to be explained. The bridge corners are connected to the wave filters WF-1 and WF-2 and to the terminals 1, 2 as in Fig. 3.

The valve V is provided with a grid leak comprising two resistances R_7 and R_8 in series, and R_7+R_8 should preferably be large compared with the impedance of the condenser C_3 at the synchronising frequency. The anode is supplied with potential from a battery or other source S through a load resistance R_9 , and a conventional cathode resistance R_5 shunted by a condenser C_5 (or any other suitable arrangement) may be used for biasing the control grid.

The modulating signal currents are rectified by any suitable means (not shown) and the rectified output is applied through the terminals 3 and 4 to the resistance R_7 .

The control-grid voltage so obtained will vary in accordance with the signal and will vary the amplification factor of the valve, and thus also the effective capacity connected across C_3 in the manner just explained. This will vary the phase difference F in accordance with the signal, as before.

The sense of the variation may clearly be reversed by reversing the sign of the rectified voltage supplied to terminals 3 and 4.

In this arrangement the wave filters WF-1 and WF-2 are necessary in order to ensure that the modulating currents are excluded from the generators.

It will be understood that although the valve V is shown as a triode for simplicity, it may have other electrodes (not shown) which may be provided with polarising potential in known manner. Further, the amplification factor may be controlled if preferred by applying the rectified signal voltage to one of these other electrodes instead of to the control grid in a manner which will be understood by those skilled in the art.

Figs. 3 and 4 show only two methods by which the network may be varied in the manner desired. Various other arrangements are clearly possible by which any or all of the impedances may be varied in accordance with the signal. Moreover, the type of bridge network shown is only one possible type of phase changing network that might used. Such a network could include inductances instead of or in addition to any of the impedances shown, and the impedances might be arranged in other ways; and further, it need not be a bridge network.

It will be noted that in Figs. 3 and 4 the phase splitter comprises only one phase changing network, which is connected between the terminals

1, 2 and the saw-tooth generator SG-2. Thus the phase of the saw-tooth waves from the other generator will be substantially not affected by the signal and the pulses will be modulated by shifting the leading edge (or the trailing edge) only. By connecting a second not necessarily similar network in front of the saw-tooth generator SG-1, and arranging for the signal to vary the two networks simultaneously in opposite directions, both edges may be shifted equally in opposite directions, so that the centre line of the pulse is not shifted by the modulation. This may be easily achieved in Fig. 3 by using thermistors in the second network which have a temperature coefficient opposite to that of those in the first network. This applies equally well to both types of thermistors. In Fig. 4 the same opposite variations of the two networks can clearly be obtained by applying the rectified voltage in opposite senses to the two valves.

Fig. 5 shows one example of a circuit for the mixer M. It comprises two similar thermionic valves V_a and V_b whose anodes are supplied through equal resistances X_a and X_b from a potential source S. Resistances R_a, R_b shunted respectively by condensers K_a and K_b are provided in series with the cathodes for biasing the control grids, though any other convenient biasing arrangement may be used. The outputs from the saw-tooth generators SG-1 and SG-2 (not shown in Fig. 5) are connected to the control grid circuits of the valves V_a and V_b (respectively) through the terminals 1_a, 2_a and 1_b, 2_b. The output terminals 5 and 6 are connected to the anodes of V_a and V_b respectively through blocking condensers C_a and C_b.

It will be clear that the difference of potential of the terminals 5 and 6 is equal to the difference between the anode voltages of the two valves. If therefore, each of the generators is arranged to supply saw-tooth waves of the same sign but differing in phase by F (for example SG-1 supplies a wave like A, Fig. 1, and SG-2 supplies a wave like A but shifted forwards by the time t). Then the difference between the two waves is obtained from the terminals 5 and 6, producing the pulses C. Arrangements for rendering them unidirectional if desired may be provided in any suitable way.

It will be seen that the circuit of Fig. 5 performs the subtraction of the two waves directly in a very simple way so that no additional means is necessary for inverting one of them.

What is claimed is:

1. An electrical pulse transmission system comprising two saw-tooth wave generators, means for supplying respectively each of said saw-tooth wave generators with synchronizing alternating voltages of the same frequency but differing in phase, means for varying the phase difference in accordance with a modulating signal, and means for combining the saw-tooth waves from the two generators to produce a series of regularly repeated rectangular pulse time-modulated in accordance with the signal.

2. A system according to claim 1 in which the phase splitter comprises a phase changing network connected between the oscillator and one of the generators, and is connected to said modulating signal source for control thereby.

3. A system according to claim 14 in which the phase splitter comprises two phase changing networks connected between the oscillator and the two generators, respectively, both the networks

being connected to said modulating signal source to be controlled thereby.

4. A system for deriving time-modulated electrical pulses from two saw-tooth wave generators comprising two sawtooth wave generators, a sinusoidal oscillator and a variable phase splitter connected to transmit two separate synchronizing voltages having the same frequency and a variable phase difference from said sinusoidal oscillator to the two generators respectively, said phase splitter comprising a phase changing network connected between said oscillator and one of said generators, said network comprising a bridge arrangement of impedances, means for varying the value of at least one of said impedances by a modulating signal to vary the phase of one of said synchronizing voltages, and a mixing device for subtracting the synchronizing voltage varied by the modulating signal and the other synchronizing voltage, one from the other, to produce rectangular pulses.

5. A system according to claim 4 in which each network comprises two condensers connected respectively in opposite arms of the bridge, and the 25 resistance elements of two thermistors connected in the remaining arms, the thermistors having temperature coefficients of resistance of the same sign, one pair of diagonal points of the bridge being connected to the oscillator, and the other pair to one of the generators.

6. A system for deriving time-modulated electrical pulses from two saw-tooth wave generators comprising two saw-tooth wave generators, a sinusoidal oscillator and a variable phase splitter 35 connected to transmit two separate synchronizing voltages, having the same frequency and a variable phase difference from said sinusoidal oscillator to said two generators respectively, said phase splitter comprising two phase changing networks connected between said oscillator and said two generators respectively, each of said networks comprising a bridge circuit having two condensers connected respectively in opposite arms of the bridge and the resistance elements of two thermistors connected in the remaining arms, the thermistors having temperature coefficient of resistance of the same sign, one pair of diagonal points of the bridge being connected to the said oscillator and the other pair to one of said generators, means for varying the resistance of said thermistors by a modulating signal to vary the 40 phases of and thereby the phase difference of said synchronizing voltages, and a mixing device for subtracting one saw-tooth wave from the other to produce rectangular pulses.

7. A system according to claim 6 in which the thermistors are of the indirectly heated type having heating coils, and a circuit for applying the modulating signal to said heating coils to energize them.

8. A system according to claim 6 in which the thermistors are of the directly heated type, and a circuit for applying the modulating signal to the networks together with the alternating voltage from the oscillator.

9. A system for deriving time-modulated electrical pulses from two saw-tooth wave generators comprising two saw-tooth wave generators, a sinusoidal oscillator and a variable phase splitter adapted to transmit two separate synchronizing voltages having the same frequency and a variable phase difference from said sinusoidal oscillator to said two generators respectively said phase splitter comprising two phase changing bridge networks connected between said oscillator and

said two generators respectively each of said bridge networks comprising two condensers connected respectively in opposite arms of the bridge and two ordinary resistances connected in the remaining arms, one pair of diagonal points of the bridge being connected to the oscillator and the other pair to one of the generators, a thermionic valve having a variable amplification factor shunted across one of the condensers and means to control the control grid-cathode circuit of said thermionic valve in accordance with a signal.

10. A system according to claim 9 having means for controlling the amplification factor of the valve including a circuit for applying to the control grid a rectified voltage derived from the signal voltage.

11. A system according to claim 9 further including a circuit applying the modulating signal to vary the amplification factors of the two valves simultaneously in opposite directions.

12. A system according to claim 1 in which the means for supplying the two alternating voltages comprising each generator is preceded by a wave filter adapted to pass substantially only the synchronising voltage.

13. The method defined in claim 16 in which the saw-tooth waves are combined by subtracting one from the other.

14. A system for deriving time modulated electrical pulses from two sawtooth wave generators comprising two sawtooth wave generators, a sinusoidal oscillator, means including a phase splitter for deriving from the output of said oscillator two separate synchronizing voltages having the same frequency but different phase, means for applying said separate voltages to the two sawtooth wave generators respectively, a modulating signal source, means to control the said phase splitter by said source so as to vary the phase difference of said synchronizing voltages by said modulating signal, and a mixing device for subtracting one of said sawtooth waves from the other to produce rectangular pulses.

15. An electrical pulse transmission system comprising two sawtooth generators, means for supplying to said two sawtooth generators respectively synchronizing alternating voltages of the same frequency but of different phase, said means including a sinusoidal oscillator and a variable phase splitter, a source of modulating signals and means for controlling said phase splitter by modulating signals from said source so as to vary the phase of at least one of said voltages, whereby the phase difference of said two voltages is varied by said signal source.

16. The method of transmitting a signal through the medium of regularly repeated electrical pulses which comprises producing a variable signal current, producing two alternating voltages having the same frequency but differing in phase, causing said two voltages to produce two separate sawtooth waves having the same period but separated in phase by the phase difference of said alternating voltages, controlling the magnitude of the phase difference between said alternating voltages in accordance with the variations of said signal current, and combining said sawtooth waves to produce rectangular pulses of variable duration varying in accordance with said phase difference.
